UNITED STATES PATENT OFFICE.

CHARLES H. RUGGLES, OF HOPE, ARKANSAS.

HAY-PRESS.

No. 907,408.

Specification of Letters Patent.

Patented Dec. 22, 1908.

Application filed April 23, 1908. Serial No. 428,787.

To all whom it may concern:

Be it known that I, CHARLES H. RUGGLES, a citizen of the United States, residing at Hope, in the county of Hempstead and State 5 of Arkansas, have invented a new and useful Hay-Press, of which the following is a specification.

This invention has relation to hay presses and it consists in the novel construction and 10 arrangement of its parts as hereinafter shown and described.

The object of the invention is to provide a sweep actuated mechanism for operating a reciprocating plunger in a press of the character indicated.

With this object in view the press consists primarily of a vertically disposed shaft to which the sweep is attached. The plunger bar which is arranged to reciprocate with relation to the said shaft is provided at its ends with an elongated guide which receives the said shaft and is adapted to bear against the side of the same for directing the movement of the said bar so that the movement of the 25 plunger is maintained in fixed alinement. The said guide is so mounted as to engage the side of the shaft and move in the direction in which the said shaft is turning so that the friction at the point of contact between the 30 guide and the shaft is reduced to a minimum. That is to say, as the guide moves in one direction it comes in contact with one side of the shaft and when it moves in the opposite direction it comes in contact with the opposite 35 side of the said shaft. A cross arm is fixed to the shaft and is provided at its end with rollers the peripheries of which project beyond the opposite sides of the said cross arm. That is to say, one roller projects beyond one side of the said arm while the other roller projects beyond the opposite side thereof.

A pitman bar is pivotally connected with the plunger bar and is provided at its free 45 end with a concavity adapted to receive the rollers of the cross arm and adjacent to the said concavity is located a convexity which is adapted to engage the side of the cross arm for the purpose of expelling or pushing the 50 said roller from the said concavity during certain stages of the operation of the device. A lever is fulcrumed upon the sills of the press and is pivotally connected at its working end with a laterally disposed eye located 55 upon the pitman bar in the vicinity of its pivotal connection with the plunger bar. The

power end of said lever is provided with a concavity which is also adapted to receive at times the rollers of the cross bar.

The concavities of the pitman bar and the lever are so located with relation to each other that when the plunger is at the end of its stroke in the baling chamber the said concavities are directly opposite each other and the roller which is located in the concavity of the pitman bar is delivered from the same directly into the concavity of the lever. The lever and the said pitman bar are also of such relative lengths that as one roller which is carried by the cross arm passes out of the 70 concavity of the lever the roller at the opposite end of the said cross arm simultaneously is inserted into the concavity of the pitman bar, consequently one or the other of the 75 ends of the cross arm is at all times in positive contact in either the pitman bar or the said lever and thus the sweep is continuously under tension and the whiffle-tree attached thereto and to which the draft animal is connected is prevented from whipping or interfering with the movement of the animal. The cross arm is in engagement with the pitman bar during the compression stroke of the plunger while the cross arm is in engagement 80 with power end of the lever during the retraction of the plunger. The pitman bar lies transversely across the working end of the 85 said lever and reciprocates as the said lever swings. The lever forms a guide and support for the free end of said pitman bar. 90

In the accompanying drawings: Figure 1 is a longitudinal sectional view of the press with the parts in side elevation. Fig. 2 is a perspective view of the mechanism for actuating the plunger. Fig. 3 is a plan view of 95 said mechanism showing the plunger bar advanced. Fig. 4 is a plan view of said mechanism showing the plunger bar retracted. Fig. 5 is a plan view of the plunger bar guide illustrating the same in contact with the actuating shaft as the bar advances, and Fig. 6 is a plan view of the plunger bar guide, illustrating the same in contact with the actuating shaft as the bar retracts.

The press consists of the baling chamber 1 105 which is mounted upon the sills 1'. The spring actuated dogs 2 are located in the sides of the said chamber and are adapted to retreat as the plunger 3 advances and they project into the said chamber when the said 110 plunger retreats and prevent the rearward movement of the hay after the same has been

compressed and moved longitudinally along the said chamber by the compression stroke of the said plunger. The plunger 3 is provided at its upper side with a series of spring 5 tongues 4 which are spaced apart at their ends located toward the delivery end of the baling chamber 1. The said spring tongues 4 traverse the length of the inlet 5 to the baling chamber 1 as the said plunger 3 reciprocates and they form means for doubling the 10 hay under so that the plunger will not wedge the same against the edge of the inlet 5. The plunger bar 6 is connected with the plunger 3 and lies between the sills 1' of the framework 15 of the press. The spider 7 is mounted upon the sills 1' at the opposite ends thereof from the baling chamber 1. The said spider is of tripod formation with two of its legs resting upon one of the said sills and its other leg 20 resting on the other sill. The bolster 8 is attached at its ends to the sills 1' and lies under the middle of the spider 7. The pillow bearing 9 is mounted upon the bolster 8. The lower end of the sweep shaft 10 is journaled for rotation in the pillow bearing 9 and the upper portion of the said shaft is journaled for rotation in a bearing 11 provided in the spider 7.

The sweep 12 is fixed to the upper end of 30 the shaft 10 and is provided at its free end with means for attachment with the whiffle-tree or similar draft means. The cross arm 13 is fixed to the shaft 10 and is located below the intermediate portion of the spider 7. 35 The extremities of the legs of the said spider are vertically disposed and rest upon the sills 1' as above described. The pitman bar 14 is pivotally connected with the plunger bar 6 at the point 15. Said pitman bar is provided at its opposite end with a concavity 16 at the outer end of which is located a convexity 17. The laterally disposed eye 18 is attached to the side of the pitman bar 14 in the vicinity of the pivoted end thereof.

40 The lever 19 is fulcrumed under one of the legs of the spider 7. Said lever is provided with a relatively long working end 20 and a relatively short power end 21. The working end of the said lever is pivotally connected by means of a rod 22 with the eye 18. The power end 21 of the said lever is provided with a concavity 23. The rollers 24 are journaled for free rotation at the opposite ends of the cross arm 13 and one of the rollers 24 projects at its side beyond the side of the said arms 13 and the other roller 24 projects at its opposite end beyond the opposite side of the said arm 13. The plunger bar 6 is arranged to reciprocate in alinement with 45 the vertical axis of the shaft 7 and is provided at its end adjacent the said shaft with an elongated guide 25 which surrounds the said shaft and is disposed in alinement with the vertical axis of the same. The transverse 60 dimension of the said guide 25 is slightly

greater than the diameter of the shaft 7 so that the opposite sides of the said guide cannot have contact at the same time with opposite points of the shaft 7.

The operation of the mechanism for actuating the plunger bar 6 is as follows: Through the instrumentality of an animal or its equivalent attached to the sweep 12 the shaft 7 is rotated which carries around the arm 13 in the direction in which the rollers 24 project beyond the sides of the said arm. As one of the rollers 24 passes out of the concavity 23 in the lever 19 the other roller 24 enters the concavity 16 in the pitman bar 14. Thus as the arm 13 rotates with the shaft 7 75 and the roller 24 is in contact with the surface of the concavity 16 the pitman bar 14 is moved longitudinally and the plunger bar is moved longitudinally toward the baling chamber 1. At the same time the rod 22 80 which pivotally connects the eye 18 with the work end of the lever 19 swings the said lever upon its fulcrum so that its power end is swung over the plunger bar 6. When the arm 13 has moved the pitman bar 14 until 85 the said bar and the said arm are substantially in alinement with each other the concavities 16 and 23 in the bar and lever are directly opposite each other, consequently as the arm 13 continues in its movement the 90 convexity 17 engages the side thereof and forces the roller 24 out of the concavity and delivers the same into the concavity 23 of the lever 19. Thus, the end of the arm 13 is transferred from pitman bar 14 to the working end of the lever 19 and as the said arm 13 continues in its movement said lever 19 is 95 swung upon its fulcrum in the opposite direction and through the rod 22 connected with the eye 18 said pitman bar 14 is retracted 100 in its movement which draws the plunger bar 6 toward the shaft 7. When the roller 24 moves to a point in its path where it is about to escape from the concavity 23 in the 105 end of the lever 19 the roller 24 at the opposite end of the arm 13 is about to enter the concavity 16 at the end of the pitman bar 14 110 when the operation as above described is repeated. During the reciprocation of the plunger bar 6 there is some side draft upon 115 the same due to the fact that the rod 22 connects with the laterally disposed eye mounted upon the sides of the plunger bar 14. This side draft has a tendency to bring the opposite side of the guide 25 alternately in 120 contact with the opposite sides of the shaft 7, but as the side of the guide 24 is always moving in the same direction in which the said shaft is turning the friction due to the contact between the said parts is reduced to a 125 minimum.

Having described my invention, what I claim as new and desire to secure by Letters Patent is:

1. In mechanism of the class described, a 130

vertically disposed shaft, a cross arm carried by said shaft, a reciprocating plunger bar having at its rear end an elongated recess through which the shaft extends, a pitman 5 connected to the plunger bar and having at its rear end a pocket into which the opposite ends of the cross arm successively enter to effect forward movement of the plunger bar, and a retracting lever having one end operatively connected to the pitman, the opposite 10 end of said retracting lever having a pocket which is positioned opposite the pocket of the pitman as the latter completes its stroke whereby the cross arm may pass from the 15 pocket of the pitman directly into the pocket of the retracting lever.

2. In apparatus of the class described, a vertically disposed shaft, a cross arm carried thereby, a reciprocating plunger bar having 20 at one end an elongated recess through

which the shaft extends, a pitman connected to the plunger bar and having at its rear end a pocket for the reception of the ends of the cross arm, and a retracting lever connected to the pitman, one end of said retracting lever having a pocket arranged to face the pocket of the pitman when the latter reaches the end of its stroke, the pocket of the retracting lever being so disposed that as one end of the cross arm disengages therefrom 25 the opposite end of said cross arm will enter the pocket of the pitman thereby insuring constant stress on the cross arm.

In testimony that I claim the foregoing as my own, I have hereto affixed my signature 30 in the presence of two witnesses.
